(57) **CLAIM**

The ornamental design for a tilted hanging and spinning playground device, is shown and described herein.

DESCRIPTION

FIG. 1 is a perspective view of a tilted hanging and spinning playground device design;

FIG. 2 is a left side elevational view thereof, the right side view being a mirror image thereof;

FIG. 3 is a front elevational view thereof;

FIG. 4 is a rear elevational view thereof;

FIG. 5 is a top plan view thereof; and,

FIG. 6 is a bottom plan view thereof.

The broken line showing is included for the purpose of illustrating and forms no part of the claimed design.
